GUIDE BAR ATTACHMENT

Harold O. Cadman, Rockton, Ill., assignor, by
mesne assignments, to Gardner Machine Com-
pany, a corporation of Illinois

Application November 9, 1949, Serial No. 126,376

2 Claims. (Cl. 51—112)

1

The present invention pertains generally to attachments for channeling workpieces through the work zone of a grinding machine and more specifically to an improved device of this nature having novel means for tensioning a pair of guide bars extending through the grinding zone defined by a pair of axially spaced abrasive wheels.

In order to guide relatively thin workpieces through the work zone of a grinding machine, resort is commonly had to the use of a pair of laterally spaced guide bars having a thickness substantially less than the distance between the abrasive wheels. The thickness of the guide bar in such instances may run as low as $\frac{1}{2}$ ". Under normal operating conditions, even slight contact between the abrasive wheels and either of such thin guide bars would produce sufficient frictional heat to progressively distort the bar, resulting almost immediately in the severing of the bar with consequent spillage of the workpieces and shutdown of the machine. Heretofore, it has been customary to adjustably attach the guide bars to a pair of rigid posts, one being located near the entrance and the other near the exit of the grinding zone. The initial adjustment is made in such a manner that the guide bars are tensioned by the inherent spring of these posts. Under high speed operation, however, considerable heating of the guide bars occurs and causes them to expand proportionately. For example, a guide bar 26" in length may rise from room temperature to 300° F. during the grinding operation, resulting in a total linear expansion of as much a .050". Since the springiness of the rigid supporting posts is normally insufficient to absorb this amount of expansion, the tension of the guide bars tends to slack off to an undesirable extent with consequent danger of contact with the grinding wheel and severance in the manner outlined above. Moreover, the conventional type mounting arrangement is very apt to produce unequal tensions in the guide bars whereby one bar may remain fairly taut and the other may be so slack that it flexes excessively.

Accordingly, one object of the invention is to provide a guide bar attachment for a grinding machine and which will have a novel tensioning arrangement for the guide bars, such arrangement being substantially unaffected by the thermal expansion of the bars incident to operation of the machine.

Another object is to provide an attachment of the foregoing character wherein the tension-

ing means, after initial adjustment, will maintain the bars under substantially equal tension for various operating conditions.

A further object is to provide a bar tensioning means of the type set forth which will be of simple, rugged and economical construction, yet capable of adjustment with a high degree of nicety and precision.

Other objects and advantages will become apparent as the following detailed description proceeds, taken in the light of the accompanying drawings wherein:

Figure 1 is a fragmentary elevation of an illustrative guide bar attachment embodying the present invention, the abrasive wheels of a grinding machine and a portion of their housing being shown fragmentarily.

Fig. 2 is a fragmentary plan view of the device shown in Fig. 1.

Figs. 3, 4 and 5 are enlarged transverse sectional views through the illustrative guide bar attachment, such views being respectively taken in the plane of the lines 3—3, 4—4 and 5—5 in Fig. 2.

Fig. 6 is an enlarged fragmentary plan view detailing one of the spring members embodying the invention, together with its supporting means.

Fig. 7 is an enlarged fragmentary perspective view showing details of the tensioning spring end of the device of Fig. 1, one of the abrasive wheels being omitted for purposes of clearer illustration.

Fig. 8 is an enlarged fragmentary perspective view detailing in exploded form the fastening means used between one of the guide bar ends and its tensioning spring.

While the invention is susceptible of various modifications and alternative constructions, a preferred embodiment has been shown in the drawings and will be described below in considerable detail. It should be understood, however, that there is no intention to limit the invention to the specific form disclosed, but on the contrary, the intention is to cover all modifications and alternative constructions falling within the spirit and scope of the invention as expressed in the appended claims.

Upon more specific reference to the drawings, it will be perceived that there is shown an illustrative guide bar attachment 10 embodying the invention and comprising a pair of rigid upstanding bed-plates 11, 12 which straddle a grinding zone defined between a pair of axially spaced abrasive wheels 14, 15. The latter are drivingly mounted in any appropriate manner upon a

2

grinding machine, the details of which are unimportant for present purposes. The abrasive wheels 14, 15 are housed within a relatively heavy protective hood 16 fixed to the base of the grinding machine and having diametrically opposed mounting faces 17, 18 to which the bed-plates 11, 12 are rigidly attached. Running through the grinding zone and having their end portions projecting through vertical slots 19 in the bed-plates 11, 12 are a pair of spaced apart parallel guide bars 20, 21. As indicated in Fig. 4, the guide bars 20, 21 are of relatively thin strap stock, having a thickness which is only a fraction of the distance between the grinding wheels 14, 15 so as to provide clearance with the latter. When properly tensioned so as to eliminate any tendency for buckling or flexure, the guide bars 20, 21 define a workpiece supporting path running diametrically through the grinding zone.

Workpieces such as piston ring blanks R may be fed in a procession to the attachment 10 by the use of an appropriate feed mechanism. While the details of such a mechanism form no part of the present invention, there is shown merely for the sake of completeness certain feed mechanism guide members which terminate at the attachment 10. As indicated in Figs. 1, 2 and 3, such members may comprise upper and lower guide rails 22, 24, respectively disposed in alignment with upper and lower guide bars 20, 21. Located between the rails 22, 24 but spaced in straddling relation with the path of movement of the workpieces are a pair of side guides 25, 26. The latter are rigidly fixed as by means of bolts 28 to a pair of mounting flanges 29 (Fig. 3). Each of the flanges 29 is integral with a corresponding plunger 30 slidably supported in a head 31 projecting from the face of the plate 11. Each of the plungers 30, together with its respective one of the side guides 25, 26 may be adjusted laterally of the path of workpiece movement as by means of an adjusting knob 32.

For the purpose of supporting the ends of the guide bars 20, 21 projecting through the bed-plate 11 against longitudinal movement while permitting adjustment of the same laterally relative to each other, the bed-plate 11 is formed with a flat way 34 extending vertically thereof (Fig. 3). Slidably mounted on the way 34 are a pair of anchor blocks 35 which are supported by means of a common adjusting screw 36. The latter is journaled in ear 37 fixed to the plate 11 and threadedly engages aligned bores in each of the blocks 35. The upper portion of the screw 36 is threaded in the opposite sense from its lower portion. Consequently, rotation of the screw 36 by means of its adjusting knob 33 in one direction will cause the blocks 35 to move toward each other while rotation of the knob 33 in the opposite direction will cause the blocks to move away from one another. Pivottally secured as at 39 to the upper anchor block 35 is the left hand end portion of the upper guide bar 20 (as viewed in Fig. 1). By the same token, the left hand end portion (as viewed in Fig. 1) of the lower guide bar 21 is pivotally fixed to the lower anchor block 35 as at 40. When the end portions of the guide bars 20, 21 have been properly positioned by shifting the anchor blocks 35 through the use of the screw 36 and adjusting knob 33, the adjustment may be preserved by clamping the anchor blocks 35 against movement along the way 34. This is accomplished in the present instance by the use of a T-slot 41 ex-

tending longitudinally of the way 34 and adapted to receive the heads of clamping bolts 42 carried by the blocks 35. Each of the bolts 42 may be clamped simply by tightening its nut 44.

5 In order to provide a corresponding lateral adjustment for the opposite end portions of the guide bars 20, 21, the bed-plate 12 is provided with a vertical way 45 similar to the way 34 (Figs. 1, 2 and 5). A pair of anchor blocks 46 is slidably supported on the way 45 by means of a screw 47 similar to the screw 36 and rotatably mounted in ear 48 fixed to the plate 12. The blocks 46 may be shifted toward or away from one another simply by turning adjusting knob 49 of the screw 47 in the proper direction. To clamp the blocks 46 in a desired condition of adjustment, the way 45 has a T-slot 50 which receives the heads of clamping bolts 51 carried by the anchor blocks 46.

20 Means is provided for maintaining each of the guide bars 20, 21 under sufficient tension to prevent flexure, regardless of the degree of thermal expansion incident to the grinding operation. This is accomplished by interposing an individual tensioning means between one end of each

25 guide bar and its supporting member, either directly or by the use of an appropriate mechanical connection, such means being adapted to exert a substantially constant tension regardless of the degree of thermal expansion in its corresponding guide bar.

30 The opposite end of each guide bar is, of course, constrained against longitudinal movement relative to the other supporting member. Accordingly, in the attachment 10 the end 35 of each of the guide bars 20, 21 projecting through the bed-plate 11 is connected to its anchor block 46 by means of a well loaded tension spring 52 having a comparatively high spring scale. In the present instance, each of the springs 52 com-

40 prises a relatively heavy bar of resilient stock bent into a general U-shape. One arm of the spring abuts against its associated anchor block 46, being secured thereto as by means of the clamping bolt 51. The other arm of the spring 45 is adapted for attachment to the adjacent end of its corresponding guide bar. As shown in Figs. 7 and 8, such attachment means may include an integral lug 54 of reduced cross section which extends into a slot 55 near the end of the guide bar.

50 To preclude tearing of the metal between the slot 55 and the end of the guide bar, a slotted reinforcing shoe 53 may be provided. In attaching the guide bar to the spring 52, the shoe 53 is first inserted into the slot 55 and pushed toward the end of the bar. The parts are so proportioned that this will leave just sufficient clearance to comfortably insert the lug 54 between the bottom of the shoe 53 and the far wall of the slot 55.

60 By reason of the foregoing structure, it will be apparent to those skilled in the art that a thermal expansion or contraction in one of the guide bars of as much as .050" will produce only a slight deflection of its spring 52. Moreover, 65 due to the fact that the spring 52 is designed to operate in a substantially loaded condition, such deflection will have an almost negligible effect upon the tension in the guide bar. In addition, if the guide bars 20, 21 have been initially set up with substantially equal tension, unequal expansion or contraction in the bars 70 will have little if any effect upon their relative tensions.

75 To provide a convenient means for relieving the tension in the springs 52 so as to facilitate

assembly and disassembly of the guide bars thereon, a machine screw 56 is threaded onto each of the anchor blocks 48 and passes through aligned transverse holes in the arms of each spring 52. Tightening of the screw 56 will of course cause its head to force the longer spring arm toward the shorter arm and the spring tension force will thereupon be transferred to the screw 56. This arrangement normally produces sufficient deflection of each spring 52 to permit the slotted end of its associated guide bar to be readily slipped over the lug 54. Under normal operating conditions, however, the screw 56 is backed off to a point where there is considerable clearance between its head and the spring arm (Fig. 6). Under such circumstances, the guide bar alone carries the spring tension. Where a high degree of tension is desired in the guide bars, it may be found convenient to interpose a supplementary compression spring 58 between the arms of each of the springs 52. In such installations, the screw 56 constitutes a convenient guide for the spring 58.

Where the attachment 10 is mounted with its guide bars 20, 21 disposed in a substantially horizontal direction, it might be necessary to resort to side guides 59, 60 adjacent the plate 12. These elements straddle the path of movement of the workpieces and are substantially similar to the side guides 25, 26 described earlier herein. Like the latter, the side guides 59, 60 are carried by plungers 61 slidably housed in heads 62 projecting outwardly from the bed-plate 12. The guides 59, 60 may be adjusted as by means of knobs 64, similar to the knobs of the guides 25, 26.

I claim as my invention:

1. The combination of a grinding machine having a work zone defined between a pair of axially spaced abrasive wheels with a guide bar attachment comprising a pair of upstanding bed-plates rigidly mounted with one adjacent the entrance end and with the other adjacent the exit end respectively of the work zone, each of said bed-plates having a vertical way with a T-slot therein, two pairs of spaced apart anchor blocks, each pair being disposed to slide along the way of a respective one of said bed-plates, vertical adjusting screws disposed in threaded engagement with respective pairs of said blocks and adapted to position the blocks of either of said pairs at various selected distances apart, clamping means

engageable with the T-slots for securing said pairs of anchor blocks in desired conditions of adjustment, a pair of relatively thin normally flexible guide bars disposed in spaced relation and extending through the work zone and between said bed-plates, said guide bars being disposed in substantially perpendicular relation to the vertical ways of said bed-plates, means pivotally securing the two ends of said guide bars adjacent one of said bed-plates to the anchor blocks of said one bed-plate, and substantially U-shaped tensioning springs connected between the opposite ends of said guide bars and corresponding ones of said anchor blocks on the other of said bed-plates, each said spring being mounted with one leg fixed to its associated anchor block and the other leg disposed for the application of tension longitudinally of its associated guide bar.

2. In a guide bar attachment adapted for supporting a procession of workpieces passing through the work zone of a grinding machine, the combination of a U-shaped guide bar tensioning spring having an extension at one end thereof for insertion in a slot adjacent the end of a guide bar, a reinforcing shoe also insertable in the slot and adapted to abut said extension, a compression screw mounted transversely of said U-shaped spring and adapted when tightened to relieve the initial tension therein, and a supplementary compression spring disposed in surrounding relation upon said screw, said supplementary spring being interposed between the ends of said U-shaped spring to augment the tension produced by the latter in the guide bar.

HAROLD O. CADMAN.
